UNITED STATES PATENT OFFICE.

JOHN Q. SHERMAN AND ALBERT W. METZNER, OF DAYTON, OHIO; SAID METZNER
ASSIGNOR TO SAID SHERMAN.

FLAT-BED MANIFOLDING MACHINE.

Application filed December 27, 1920. Serial No. 433,208.

To all whom it may concern:

Be it known that we, JOHN Q. SHERMAN and ALBERT W. METZNER, citizens of the United States, and residents of Dayton, in 5 the county of Montgomery and State of Ohio, have invented certain new and useful Improvements in Flat-Bed Manifolding Machines, of which the following is a full, clear, and exact description, reference being had 10 to the drawings, forming part of this specification.

Our invention relates to flat bed manifolders of the type wherein there are a number of webs of paper with forms imprinted 15 upon the webs, the problem being to feed these webs in a convenient manner, and to align them accurately for receiving correctly located impressions upon all superimposed forms.

20 Among other things our invention is directed to means for supplying paper webs from a storage cabinet, in proper condition of alignment both longitudinally and laterally and in doing this without any separate 25 manual operation over and above those done in feeding the paper over the machine platen after they have been written upon.

It is our object to provide a means of feeding the plural webs which is adjustable for 30 different lengths of feed, and in this connection to adjust the storage feed to correspond to the "issuing" feed, so as to maintain a loop or looseness of paper between the storage device and the writing device, thereby 35 insuring a freedom of the various webs for adjustment free of frictional engagement with each other.

It is further our object to align the webs 40 of paper by means of members adapted to engage the holes in the plural forms during a period of relaxation of the normal feed.

We also provide means for insuring a 45 proper riding of the paper webs over the carbon paper employed in duplication of the impressions formed upon the topmost web, and further extend the usefulness of this means so as to serve as a member for breaking loose adhesions of carbon paper to the webs fed between it.

50 We have found that where a large number of webs of paper and carbon paper are used that it is very difficult to get proper feed and registration, and our invention is direct-

ed to the handling of up to a dozen or more webs of paper, as well as to the usual two or three copies usually employed in the autographic type of manifolder.

We provide in this connection for an electric feed of the various webs on the same principle illustrated in our copending application Serial No. 370839, filed April 2nd, 1920, wherein a motor is used which automatically switches off the power by a longitudinal movement of the rotor.

These objects and other advantages to be 65 noted below, we accomplish by that certain construction and arrangement of parts to be hereinafter more specifically pointed out and claimed.

In the drawings,

Figure 1 is a side elevation of the typewriter manifolder embodiment of our invention.

Figure 2 is a continuation of Figure 1, the first two together making up a complete 75 side elevation.

Figure 3 is a detail perspective of the movable device for safeguarding the paper webs for a smooth sliding over the carbon paper, and also for jogging loose carbon paper adhesions.

Figure 4 is a view of the paper roll spindle.

Figure 5 is a detail plan view of the cover plate and sprockets of the storage cabinet 85 feeding devices.

Figure 6 is a plan view detail of the traveling bar carrying the form engaging pins of the storage feeding device.

Figure 7 is a side elevation of the paper 90 feed used on the writing machine or register.

Figure 8 is another view similar to Figure 7 showing the said feeding device in a position of adjustment for a short feed.

Figure 9 is an edgewise view of the pressure roll elevating cam.

Figure 10 is a view of the part shown in Figure 9.

Figure 11 is a perspective view of the primary member of the adjustable feed element.

Figure 12 is an edgewise view of the said primary member.

Figure 13 is a perspective view of the secondary member of the adjustable feed element.

Figure 14 is an edgewise view thereof.

Figure 15 is a perspective view of the third member of the adjustable feed element.

Figure 16 is an edgewise view thereof.

Figure 17 is a plan view of the retaining 5 ring.

Figure 18 is a side view thereof.

Figure 19 is a detail end elevation showing the new form of adjustable feed.

Figure 20 is a side elevation on a small 10 scale showing the application of the feed principle to autographic registers.

Figure 21 is a perspective detail showing the application of an electric feed device to the flat bed machine.

15 Figure 22 is a detail side elevation of the switch operating mechanism and feed trip for the feed shown in Figure 21.

In view of the fact that this invention embodies a novel form of feed for a plurality 20 of strips of paper, whereby the length of paper that is fed during one complete continuous operation of the machine may be varied through wide limits by means of an adjustable mechanism, and whereby the various paper webs may be aligned by a mechanism operable in connection with the feeding mechanism, so as to bring the webs into an accurate line for line superimposition;—we will first describe said feeding and 25 aligning mechanism, and then describe the modes of application to manifolding machines, and particularly to typewriter machines dealing with a large number of webs of paper.

30 Referring to Figures 7-21, it will be noted that the surface upon which the writing is to be done, otherwise called the tablet or platen, is indicated at 1, and a spring-pressed tension roller or its equivalent is indicated at 2. Mounted beneath the platen or tablet is a rotary shaft 3, known as the feed shaft, which is revolved by the operator in order to feed the paper along the platen or tablet.

35 The feeding devices mounted on the feed shaft, are in this instance shown as three in number and arranged in two sets although these numbers are merely adopted as showing a convenient embodiment of the invention. Each device is a segmental plate having a periphery which passes through a slot or suitable clearance left beneath the tension roll, in the tablet or platen. Thus the platen may be cut away into slots 4, as shown, 40 or it may terminate ahead of the vertical plane of the tension roll, as desired.

45 Of the three elements the first as shown at 5, has a hub 6 mounted fast on the feed shaft, and a periphery 7, the foremost point 50 on the periphery being equipped with a feed pin 8. At the rearmost edge of this element is formed a lug within which is a threaded hole 9. The second element 10 has an arcuate slot 11 therein, and a periph- 55 ery 12 of preferably like length to that of

the first element. The hub 13 of the second element is loosely mounted over the feed shaft, and the piece lies adjacent to the first piece. This second piece has also a lug 14^a within which is a threaded hole 14.

70 The third piece or segment plate, as 15, is loose on the feed shaft and has a periphery 16, said periphery being of a length alike to that of the other two pieces, and the three pieces preferably having peripheries 75 which make up almost a complete circle when set as extensions of each other. The third piece has an arcuate slot 17, terminating within the body of a lug or extensions 18.

80 There are clamp screws 19 provided which engage in the threaded holes of the first two pieces, and lie in the slots of the second two pieces, so that the three pieces may be moved fanwise to a position wherein their peripheries are in juxtaposition with each other, or swung out so as to form continuations of each other. The clamp screws secure the pieces fast together in the desired positions, and the combined peripheries will extend as the feed shaft is rotated, 85 to a point of engagement with the tension roll, making up an arc of the desired extent.

85 As shown the peripheries may be marked off or graduated so that the operator may by reading the number of inches as per the 90 graduations determine accurately the combined length of surface presented to the tension roll during any one complete rotation of the feed shaft.

95 In addition to the above parts we mount 100 fixedly upon the feed shaft preferably at both ends thereof, a cam member 20, which strikes the tension roll during the rotation of the feed shaft and lifts it up, so that the tension is removed. This cam member is positioned so that during the period that the pins on the primary member of the feed device are uppermost the tension will be 105 lifted.

110 The paper employed with our invention is usually printed up into forms, which forms are to be filled out while on the tablet or platen, and the notations on the uppermost form transposed to the forms beneath it by means of carbon paper, or other means. 115 The paper is also formed with holes located in a line across the forms, there being in the example now being described two holes (not shown), arranged at the head of each form in like positions for each form, and located 120 and shaped so that the pins on the primary member will readily and easily enter them.

125 The feed operates as follows: When the operator has adjusted the segment plates in the desired position he rotates the feed shaft. This will cause the peripheries of the plates to engage the paper lying on the upper surface of the platen, and with the co-operation of the spring-pressed tension roll, feed the 130 pieces a given distance depending upon the

fan-wise adjustment of the said plates or segments.

After the combined peripheries of the pieces have passed beneath the tension roll, 5 the feed will cease, and the final motion of the feed shaft during its complete rotation will bring the pins on the primary segment plates into engagement with the holes in the paper webs, the tension roll being raised at 10 the same time. The pins will draw the paper along with them through a short path sufficient to adjust the holes of all webs over the pins, and thus align the paper, said paper being loose during this motion so as to permit a ready adjustment.

The tension roll is grooved out at 21 to give clearance for the pin operation, and prevent the paper slipping up off the pins, even though the roll is out of frictional contact.

At the start of the next feed, the pins may still impart a slight feeding movement, if desired, after which the tension roll will fall against the peripheries of the feeding elements, and the friction feed will take place as before.

In Figure 7 one of the feeding devices is shown as in fully expanded condition, there being a space left adjacent the pin position, 30 so as to further free the paper for pin action even where the full feed is desired.

In Figure 8 the feed devices are shown as folded up on each other as for the shortest length of feed.

35 Both devices where there are two, need not be adjusted for the same length of feed, as it may be desirable to set the paper webs over the platen so that one of the webs is engaged by only one of the feed devices, whereupon it 40 may be fed a less distance than the others.

Modifications in size, number, and arrangement of the said feeding devices, pins, and cams are fully contemplated in our invention.

45 Referring now to the inclusion of this feed in the simplest form of manifolder, viz:— the autographic register, we have shown a register casing 22, in the lid of which is mounted the friction roll 23, its ends being 50 spring-pressed downwardly at 24. The feed shaft is shown at 25, having a handle 26, which is stopped at the end of each complete rotation by means of a depressible stop 27. The paper is shown at 28, mounted on suitable spindles, and feeding in continuous webs over a tablet plate when they pass beneath the tension roll. The feeding devices are shown at 29, located in a position of about three quarters of a full possible feed.

60 After having adjusted the feeding devices to the proper length of feed the operator draws his forms over the writing tablet and mounts the holes at the heads of the forms over the pins on the primary members of the feeding devices. After making the desired

marks on the uppermost sheet, he releases the stop and turns the operating handle through one revolution, after which it comes back against the stop. During this motion the operation of the feeding devices will be 70 as described.

In a manifolding machine, such as those used in typewriting a large number of copies upon various business forms the provision of various safeguarding mechanisms is ob- 75 ligatory. The feed is the same as that now described generally, and as applied to auto-graphic registers. Referring to Figures 1, 2 and 3, it will be noted that the paper 30 passes over the platen 31 interleaved with 80 carbon paper 32, which it will be understood is mounted in some suitable way so as to pass in separate sheets or webs, transversely of the path of the paper over the platen.

The friction or tension roller 33 is mounted 85 on the ends of arms 34, which are pivoted at 35 along-side of the platen, and impelled by springs 36, to maintain the roller down against the feeding devices. For purposes of clearness the operating handle 37 aligning 90 pin 37^a, and feed shaft 38 are shown, but no other parts of the paper feed other than the cam member 39. The feed will be the same in all respects as that which we have described.

95 The various webs of paper on which the forms to be filled out are printed, pass onto the frame 40 of the typewriter manifolder over a carbon paper guarding device. Thus there are a pair of channeled uprights 41 at 100 each side of the back end of the machine, these uprights being adapted to receive a plurality of shafts or bars 42, which have enlarged heads 43 to serve as spacers. The paper webs are brought up over these bars 105 or rollers, and thus separated from each other. On each bar is mounted a pair of semi-flexible sheets 44, which may be of thin metal or other material, and which extend from the bars, forwardly of the machine, 110 passing over a roll or bar 45, and arranged at their forward ends so that between the two leaves of each pair is a sheet of the carbon paper.

115 The roll or bar 45 is mounted on a pair of extensions 46, from the two uprights, hitherto mentioned, and the structure of the two uprights and two extensions is mounted on the inside of the machine frame so that it will slide longitudinally thereof.

120 Preferably a channeled guide 47 is provided for each side of the frame, just below its upper edge, with the extensions 46 provided with a rib 48 to slide in said guides, one or both of the extensions having a handle 125 49 by means of which the movement is accomplished.

130 When the webs of paper to be written upon are brought up spaced between the guard carrying bars or rolls and led forward

over the platen, they will be separated by the shield or guards made up of the pairs of sheets 44. The carbon paper is interleaved between the webs of paper, but the meeting edges of the carbon paper sheets are set between the ends of the shields, so that they are protected.

After the writing has been done, and it is desired to feed the webs forwardly over 10 the platen, the operator may move the shield carrying frame structure forwardly, so as to run the various shields in between the carbon paper and the paper written upon, thereby breaking up any adhesions, and 15 smoothing out the assembly so that it will feed regularly without unequal friction or pull back. As has been stated, we have found that one of the chief difficulties in the handling of a large number of webs 20 of paper together with interleaved carbon paper is that the carbon paper, unless of perfect quality will stick to the paper, thereby causing trouble both in the paper feed, and in the destruction of the carbon 25 paper.

It will be noted further that as a result of this device for freeing the webs of paper from all adhesions and shielding the carbon edges, the paper is put into a condition 30 of hardly any friction or tension at all so that during the operation of the feeding devices there will be perfect freedom of adjustment of the webs on each other, when they are called to do so.

35 It is necessary, however, to provide a loose portion of paper between the storage devices, in which the paper is stored in rolls of convenient size, and the writing mechanism. Unless this is done, the paper will 40 not be free for the adjustment referred to.

In order to do this we provide a method of withdrawing the webs of paper from the feeding device, and maintaining a loop of 45 paper at all times, by means of coupling up the paper feed now described with the storage cabinet feed, and leaving a loop of paper in an amount sufficient to leave a freely hanging portion at all times between the two feeds.

50 Thus there is the cabinet 50, in which the paper is stored in rolls 51, said paper being mounted on spindles 52, which have core filling disks 53 thereon.

The paper then passes up over inter- 55 spaced idler rolls 54, and thence over a plate 55, which has formed lengthwise thereof slots 56, having a wavy outline, and terminating in large ends 57. A top plate 58, having like slots therein, is hinged at 60 59 to the cabinet, and when folded down over the paper, is spaced away therefrom and rests against a stop 60, on a bracket at the forward end of the cabinet. At this point a latch 61 engages a nose 62 on the end of the plate, this latching device being

duplicated on each side of the machine, by preference.

Mounted on a fixed shaft 63, beneath the supporting plate for the paper webs, are sprockets 64 and mounted in a bar 65 is 70 another shaft 66, which also carries sprockets 67 similar to the sprockets first mentioned.

The bar 65 is adjustable in its position lengthwise of the cabinet, by means of guides 68 in which the bar slides, and screws 69 engaging in the bar, and in screw blocks 70 at the forward ends of the guides, a set screw 71 being used to lock the adjusted position of the said bar. 75

A like sprocket to the ones mentioned is mounted on the feed shaft of the writing mechanism, as shown at 72, so that when the feed shaft is revolved the sprocket 72 is revolved, and a chain 73 is passed over the several sprockets, said chain being adjustable for length by the removal of links in any usual manner. 85

Mounted at desired points on the chain, and spaced apart the length of the desired length of paper to be fed, are short bracket pieces 74, which, as shown, are formed with channeled ends 75, which are embraced with removable chain links 76, so as to be positioned as desired in the chains. 90

The brackets carry cap screws 77 which engage in elongated slots 78, in cross bars 79, which are thus carried by the chains and are free to oscillate. These bars carry pins 80, which will enter the holes in the heads of the forms and as the chains are moved will feed the forms forwardly from the storage cabinet into a loop 81 arranged between the storage cabinet and the frame of the writing mechanism. 95

It should be understood that in referring to the number of pins used and the position of the holes, we are merely referring to a convenient arrangement and not intending to limit the scope of our invention. 100

A full complement of bars and pins is not shown, but it will be understood that the webs of paper will be arranged so that the pins will enter the holes in the continuous web and feed along a full length form or check each time that the paper feed is operated in the writing mechanism. 115

Should it be desired to operate the paper feed by electric motor, this will be readily possible in the mechanism now described, either for the autographic type or the larger machines using more paper. 120

Thus the small motor 89 may be provided, same being of the type referred to in our application for patent Serial No. 370839, filed April 2nd, 1920, which, as illustrated in said application, drives the feed shaft of the machine through the medium of a gear 90. The motor has a switch button 81^a, and the feed shaft has a cam 82 thereon which 125

is engaged by means of a latch 83, spring-pressed to latching position at 84.

A lever 85 is mounted on the side of the machine and carries a butt hinged pawl 86, 5 which when the lever is depressed will contact with a pin 87 on the latch and depress it, thereby releasing the feed shaft. The pawl when swung down into position to depress the latch will be located so that the 10 latch can rise, although the depressed position of the pawl be retained, since the pawl will then swing on its hinge, and will have to be elevated again before the latch releasing 15 operation can be accomplished.

The lever 85 may also carry an arm 86^a, 15 which will depress the switch button, whenever the latch is released. The motor as per the above noted application will be such that it will turn off of itself, when any considerable 20 load is opposed to its continued operation, so that when the feed is stopped the motor will stop of itself. A spring 88 controls the normal position of the lever 85.

Having thus described our invention, what 25 we claim as new and desire to secure by Letters Patent, is:

1. In a manifolding machine, the combination with a stationary platen, of means for feeding paper over the said platen in 30 uniform lengths at each operation, said lengths amounting to one complete fill or other form, a storage cabinet, means on the storage cabinet for feeding a like length of paper toward the platen at each operation, 35 and interconnecting mechanism between said two feeding means whereby the operation of the one will operate the other, said means for feeding over the platen having elements for aligning the length of paper 40 with each other.

2. In a manifolding machine, the combination with a stationary platen, of means for feeding paper over the said platen in uniform lengths at each operation, said 45 lengths amounting to one complete fill or other form, a storage cabinet, means on the storage cabinet for feeding a like length of paper toward the platen at each operation, and interconnecting mechanism between 50 said two feeding means whereby the operation of the one will operate the other, and means for adjusting the length of feed for both feeding mechanisms for each operation, said means for feeding over the platen having elements for aligning the length of paper 55 with each other.

3. In a manifolding machine, the combination with a stationary platen, of means for feeding paper in full form lengths over 60 said platen, and means for engaging holes formed in said paper for aligning it during a portion of the feeding operation, a storage cabinet, means on the storage cabinet for feeding a like length of paper toward the platen at each operation, and interconnect-

ing mechanism between said two feeding means whereby the operation of the one will operate the other, said means for feeding over the platen having elements for aligning the length of paper with each other. 70

4. In a manifolding machine, the combination with a stationary platen, of means for feeding paper in full form lengths over said platen, and means for engaging holes formed in said paper for aligning it during a portion of the feeding operation, a storage cabinet, means on the storage cabinet for feeding a like length of paper toward the platen at each operation, and interconnecting mechanism between said two feeding means whereby the operation of the one will operate the other, and means for adjusting the length of feed for both feeding 75 mechanisms for each operation, said means for feeding over the platen having elements for aligning the length of paper with each other. 80

5. In a manifolding machine, the combination with a stationary platen, of means for feeding paper in full form lengths over the said platen in uniform lengths at each operation, a storage cabinet, means on the storage cabinet for feeding a like length of paper toward the platen at each operation, 95 and interconnecting mechanism between said two feeding means whereby the operation of the one will operate the other, both of said feeding means having rotary sprockets, and said interconnecting mechanism comprising 100 a chain connecting said sprockets, said means for feeding over the platen having elements for aligning the length of paper with each other. 100

6. In a flat bed manifolding machine, the combination with a feed for paper adjustable for length of feed imparted to the paper during complete rotations, a feed shaft therefor adapted to be rotated one complete revolution for each feed, a latch to stop the feed shaft at each revolution, an electric motor for driving the feed shaft, said motor being adapted to automatically shut off upon stopping of the feed shaft, and a movable member for switching current into said motor. 105

7. In a flat bed manifolding machine, the combination with a feed for paper adjustable for length of feed imparted to the paper during complete rotations, a feed shaft therefor adapted to be rotated one complete revolution for each feed, a latch to stop the feed shaft at the end of each revolution, an electric motor for driving the feed shaft, said motor being adapted to automatically shut off upon stopping of the feed shaft, and a movable member for switching current into said motor, and means for providing the latch for the feed shaft with a member for operating the movable switch member, whereby an operation of the latch will re- 110

lease the feed shaft and set the motor into operation.

8. In a manifolding machine, the combination with a stationary platen, of means for feeding paper over the said platen in uniform full form lengths at each operation, a storage cabinet, means on the storage cabinet for feeding a like length of paper toward the platen at each operation, and means for synchronizing the feed of the former and the latter said means for feeding over the platen having elements for aligning the length of paper with each other.
- 15 9. In a manifolding machine, the combination with a stationary platen, of means for feeding paper over the said platen in uniform full form lengths at each operation, a storage cabinet, means on the storage cabinet for feeding a like length of paper toward the platen at each operation, and means for synchronizing the feed of the

former and the latter, and common means for actuating them in such relation, said means for feeding over the platen having elements for aligning the length of paper with each other. 25

10. In a manifolding machine, the combination with a stationary platen, of means for feeding paper over the said platen in uniform full form lengths at each operation, a storage cabinet, means on the storage cabinet for feeding a like length of paper toward the platen at each operation, and means for synchronizing the feed of the former and of the latter, said means comprising at least in part an operative connection whereby the operation of one of the feeding means will effectuate the operation of the latter said means for feeding over 30 the platen having elements for aligning the length of paper with each other. 35

JOHN Q. SHERMAN.
ALBERT W. METZNER.
